UNITED STATES PATENT OFFICE

2,317,106

SPEED DRILL

Arthur A. Nummeling, Inglewood, Calif.

Application October 1, 1941, Serial No. 413,230

2 Claims. (Cl. 77—7)

The present invention relates to new and useful improvements in hand-operated drills and has for its primary object to provide a magazine feed for the drill bit to selectively feed a bit of desired size into position in the chuck of the drill.

A further object is to provide a device of this character of simple and practical construction, which is efficient and reliable in performance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which:

Figure 1 is a side elevational view of the drill.

Figure 2 is a similar view of an opposite side of the drill.

Figure 3 is a vertical sectional view taken substantially on a line 3—3 of Figure 1.

Figure 4 is a transverse sectional view taken substantially on a line 4—4 of Figure 3, and

Figure 5 is a fragmentary vertical sectional view taken substantially on a line 5—5 of Figure 3.

Referring now to the drawings in detail wherein for the purpose of illustration I have disclosed a preferred embodiment of the invention, the numeral 5 designates the tubular shank of the drill having a sleeve 6 rotatably mounted on the lower end of the shank, the lower end of the sleeve being externally threaded for threadedly attaching the shell 7 of a chuck member thereto. The chuck member 7 is provided with the usual tapering lower end 8 within which is positioned the jaw segments 9 adapted for clamping engagement with the shank portion of the bit 10 which projects through the lower end of the chuck.

Secured to the lower end of the shank 5 is an annular flange 11 having a central opening communicating with the bore of the shank and by means of which the drill bit may pass downwardly through the shank into the chuck, the drill bit having a head 12 formed thereon, for resting on the flange 11 to support the bit with the cutting end thereof projecting outwardly of the chuck.

Secured to the upper end of the sleeve 6 is a gear 13 engaged by a ring gear 14 having a crank handle 15 attached thereto, the gear being journaled on a screw 16 projecting laterally outwardly from the shank 5. An idler gear 17 is also mounted on the shank 5 to prevent wobbling of the ring gear 14 during the operation thereof.

Mounted on the upper end of the shank 5 is a magazine designated generally at 18 and which constitutes a handle for the drill. The magazine is of cylindrical form and includes a stationary

bottom 19 having an eccentric passage 20 threaded on the shank, a centrally disposed stem 21 rising from the bottom of the magazine and on which is rotatably mounted a barrel 22 having a plurality of longitudinal chambers 23 extending entirely therethrough and adapted to selectively register at their lower ends with the passage 20. Bits of various sizes are placed in the chambers and drop into the shank 5 when the chambers 10 are moved into registering position with the passage 20.

A cap 24 is secured to the upper end of the stem 21 by a screw 25 for closing the upper ends of the chambers.

15 The cap is provided with a sliding catch 26 having a spring 27 projecting one end of the catch downwardly for entering one of the chambers 23 to secure the barrel against rotation. A handle 28 projects laterally from the catch through a slot 29 to release the catch and permit rotation of the barrel to bring a desired bit into position for dropping into the chuck.

The sides of the barrel may be provided with indicia 30 to designate the size of the bits in the respective chambers.

25 It is believed the details of construction and manner of use of the device will be readily understood from the foregoing without further detailed explanation.

30 Having thus described the invention what is claimed as new is:

1. A magazine feed for the tubular shank of a drill bit comprising a stationary part having a passage communicating with the shank, a stem 35 rising from said stationary part, a rotary part mounted on the stem and having a plurality of chambers disposed concentrically around the stem and adapted to contain bits for entering the passage when the chambers are aligned therewith, a cap secured to the stationary part, and a stop 40 carried by the cap and releasably engaging the rotary part to secure the latter against movement.

2. A drill comprising a tubular shank, a magazine 45 at one end of the shank for selectively feeding drill bits thereto, a sleeve journaled on the other end of the shank, a chuck secured to the sleeve adapted for receiving the bits from the shank, a pinion gear secured to the sleeve, a drive gear journaled on the shank on an axis laterally to the axis of the shank and operatively engaging the pinion gear, and an idler gear journaled on the shank and engaging the drive gear, at a side 50 thereof diametrically opposite from the pinion gear, said pinion gear and said idler gear providing supports for diametrically opposite edges of the drive gear.

ARTHUR A. NUMMELIN.
